(57) **CLAIM**

The ornamental design for a stamp as shown and described.

DESCRIPTION

FIG. 1 is a rear and left side perspective view of a stamp;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top side elevational view thereof; and,

FIG. 7 is a bottom side elevational view thereof.

The broken line showings in the rear and left side perspective view of the stamp in FIG. 1 and on the bottom side elevational view of the stamp in FIG. 7 are included for the purpose of illustrating environmental structure and form no part of the claimed design.

1 Claim, 7 Drawing Sheets
